UNITED STATES PATENT OFFICE.

GEORGE A. SLEIGHT, OF HYDE PARK, NEW YORK.

SANITARY SCREEN.

1,186,345.

Specification of Letters Patent.

Patented June 6, 1916.

Application filed September 24, 1915. Serial No. 52,358.

To all whom it may concern:

Be it known that I, GEORGE A. SLEIGHT, a citizen of the United States, and a resident of Hyde Park, in the county of Dutchess and State of New York, have invented certain new and useful Improvements in Sanitary Screens, of which the following is a specification.

My invention relates to urinals, and one of the main objects thereof is to provide a screen which serves to prevent the passage of refuse of such size toward the drain pipe which would be likely to obstruct the passage of water through the urinal.

15 A further object is to provide an imperforate inclined lead to a perforated platform adapted to receive and hold disinfectants in crystal form, whereby the said disinfectant may be distributed initially over the entire 20 under surface of the screen and, as worn away, will be concentrated at the point of greatest need therefor until entirely dissipated.

25 A further object is to form the lead and platform of one piece, as by a casting or stamping, and to permanently connect the screen therewith, whereby a unit is formed for ease of installation and removal. And further objects are to provide such devices 30 which are very simple in construction, installation, and use; which are cleanly and well adapted for the purpose for which they are designed; and which are comparatively inexpensive.

35 My invention is fully described in the following specification, of which the accompanying drawings form a part, in which like characters refer to like parts in each of the views, and in which:—

40 Figure 1 is a longitudinal section taken through a urinal provided with my invention, on the line 1—1 of Fig. 2; Fig. 2 is a plan view thereof; and Fig. 3 is a section taken on the line 3—3 of Fig. 1.

45 In the drawings forming a part of this application I have shown a urinal 4 having the usual feed pipe 5 and drain 6, and, as is common, having an outer nosing 7.

50 My invention comprises a pan 8 and a screen 9 connected with the edges thereof, preferably permanently, the pan having a hook 10 integral therewith for engagement with the nosing 7, and the screen 9 having a handle 11 whereby the entire device may be 55 removed as a unit.

The pan 8 is formed of one piece of metal, such as a casting or stamping, and comprises an abruptly inclined front member 12, a gradually inclined rear member 13 extended to a point beneath the feed pipe 5, 60 and suitably inclined side members 14, the upper edges of the front and side members being flush, whereas the upper edge of the rear member is sunken with respect to the edges of the front and side members, as 65 shown in Fig. 1, to provide an inlet 15 for the disinfectant crystals; these members 12, 13, and 14, terminate at a horizontal bottom portion 16 which is perforated as shown at 17, but the members 12, 13, and 14, are 70 imperforate and serve to lead water to the bottom 16 and thus through the disinfectant held in said pan 8, and they also serve to cause the disinfectant crystals to slide toward the bottom 16 as they are worn away 75 by the water, thereby insuring a supply of the crystals at the perforated bottom 16 up to the moment of total erosion.

The crystals are introduced between the screen and pan at the inlet 15, as stated, 80 and remain within the device until erosion is complete, the inlet 15 being smaller than the crystals to confine the latter in the event of the device being removed from the urinal, but the inlet may be manually enlarged for 85 the introduction of the crystals because of the yielding of the rear edge of the screen 9, the resiliency of the metal of the screen returning said edge to normal position when 90 permitted to do so.

My invention is very simple, thoroughly sanitary, highly efficient, cleanly to handle, light, compact, and comparatively inexpensive, and, while I have shown certain preferred details of construction, I reserve the 95 right to make changes thereover, within the scope of the following claim, which do not depart from the spirit of the invention nor sacrifice its advantages.

Having fully described my invention, 100 what I claim as new, and desire to secure by Letters Patent, is:—

In combination with a urinal having a feed and a drain pipe; a disinfectant pan 105 removably arranged therein and having an integral hook formed thereon for engagement with said urinal, and a screen formed of wire mesh turned over the front and side edges of said pan to form a unit with the latter, said pan having a perforated bottom 110

and downwardly inclined front, rear, and side members leading thereto, the rear end of said screen being spaced from said pan and rear member to permit the introduction of disinfectant crystals between said pan and screen.

In testimony whereof I have signed my

name to this specification in the presence of two subscribing witnesses.

GEORGE A. SLEIGHT.
